ELIZABETH P. SMITH, OF CHICAGO, ILLINOIS, ASSIGNOR TO HERSELF
AND NORMAN H. SHERBURNE, OF SAME PLACE.

Design No. 4,832, dated April 18, 1871.

DESIGN FOR A PATTERN FOR CUTTING DRESS-WAISTS.

The Schedule referred to in these Letters Patent and making part of the same.

To all whom it may concern:

Be it known that I, ELIZABETH P. SMITH, of Chicago, in the county of Cook and State of Illinois, have invented a new and useful Design or Pattern for Cutting Dress-Waists, of which the following is a specification.

On reference to the accompanying drawing—

Figure 1 represents the scale of patterns for both the front and back of a dress-waist, and

Figure 2 is the rule employed in forming the curved lines indicated by the respective dots and figures arranged upon the scale, the central portion between the lines G and H being removed.

My invention has for its object to provide a pattern provided with a series of scales so arranged as thereby to measure, lay out, and cut dresses to fit any person; and to that end,

It consists in two separate systems of scales arranged upon one design or pattern, with scales or figures corresponding with the measurement of the person to be fitted, and arranged in such a manner as to describe the outlines of the front and back of the waist when used in accordance with the directions hereinafter given.

Also, in a rule, the sides of which are curved approximating the curves described by the figures arranged upon the separate scales, by which the requisite curve is formed upon the fabric.

I construct my pattern-scale of thick card or pasteboard, with the scale of figures, letters, and dots plainly painted thereon, according to the design shown in the drawing, the several scales being perforated at the point indicated by the dots, which admits of marking the fabric at the respective points indicated by the figures upon the scale, by which the required form is given to the separate parts of the waist, as shown by lines a and d, fig. 1.

In the accompanying drawing—

Figures 1, 2, 3, 4, and 5, marked upon fig. 1, represent the scales used in giving form to the shoulder and arm-size of the front portion of the waist.

Figure 6 represents the scale used in indicating the size of the lower portion of the same.

Figures 7 and 8 represent the scales used in determining the size of the dart portion to be cut out of the lower edge of the waist; and

Figure 9 represents the scale giving the neck-size.

A, B, and C represent the scales used in giving form to the shoulder and arm-size of the back portion of the waist;

D, the neck-size; and

E, the scale giving the size of the lower portion of the same.

In fig. 2 of the drawing—

F represents the scale and curve for giving the length and form to the shoulder of the front portion of the waist;

G is the scale for determining the length of the waist;

H is the curve for giving form to the shoulder of the back portion of the waist; and

J is the curve for giving form to the lower portion of the same; the several scales and curves being arranged upon the fabric, as hereinafter mentioned.

The manner of using my invention is as follows:

First, take the bust-measure, close under the arms, around the largest part of the bust.

Second, the waist-measure, snug around the body, at the bottom edge of the proposed dress-waist.

Third, the length of waist under the arm down to the lower edge of the waist.

Fourth, the shoulder-measure, from the top of the neck-band along the top of the shoulder to the hollow or bend of collar-bone.

Fifth, subtract the waist-measure from the bust-measure, the difference being the taper-measure of the waist.

To lay out the front of the waist—

First, place the pattern upon the fabric with the edge marked K parallel with the selvage edge of the fabric, and sufficient distance therefrom to allow for the fold or part turned under; then mark the fabric through the six holes in scale 9, upon the curved line in which is formed the figures corresponding with the bust-measure.

Second, mark through the holes in scales 1, 2, 3, 4, and 5, at the figures indicating the bust-measure, and through the holes at the right and left-hand of the figures corresponding with the bust-measure in scale 7 7.

Third, find the figures in the left-hand column of scale 6 which correspond with the waist-measure; then follow the heavy line to the right hand until you find the figures indicating the bust-measure; then mark through the holes in the same column above and below the figures; remove the pattern, and draw a curved line through the six dots or marks made in scale 9, which gives the size and form of the neck.

Fourth, draw a line through the dots or marks made in scales 1, 2, 3, 4, and 5, which gives the form and size of arm.

Fifth, take the edge of the rule marked F, placing the figure indicating the shoulder-measure upon the upper dot or mark in scale 9; move the rule until its edge intersects the dot or line in scale 1; then draw a line along the rule, which forms the shoulder.

Sixth, draw a straight line from dot to dot made in

scale 6; then take the rule with the scale of inches, placing the point G upon the dot or mark made through scale 5, moving the rule until the figure indicating the length of waist intersects the line made in scale 6; then draw a line along the rule, which gives the length and form of the lower part of the waist.

Seventh, place the pattern upon the fabric as before; draw a line across the bottom of the waist; dot the fabric through the hole at e; also through the holes in the three columns containing the corresponding figures, as obtained by subtracting the waist-measure from the bust-measure.

Eighth, remove the pattern; place point G of the rule on the dot made through the pattern to the left of the column of figures in scale 7, allowing the edge to intersect the dot made through the hole e, drawing a line along the rule from point G to dot; then turn the rule reverse side up, allowing point G to remain upon the dot in scale 7; move the rule to the right to intersect the first dot made through scale 8; draw a line from point G to dot; then move the rule to the right until point G is upon the dot made to the right of the column of figures in scale 7 and the edge of the rule on the right-hand dot in scale 8; draw a line from point G to dot; then turn the rule right side up, allowing point G to remain on the dot, moving the rule until its edge intersects the second dot to the right of the hole e; draw a line from point G to the dot as before, which completes the form of the front portion of the waist.

To lay out the back portion of the waist—

First, place the perforated line of the pattern, as indicated by dots, upon the edge of the fabric; dot through the hole formed in the column of figures indicating bust-measure in scale D; also through the holes in scales A, B, and C, at the figures corresponding with bust-measure.

Second, dot through the holes in scale E E in the column of figures in which is found the numbers indicating waist-measure.

Third, remove the pattern; draw a straight line from dot to dot in scale E E.

Fourth, draw a curved line from dot in scale A through the dot in scale B to the dot in scale C.

Fifth, place the rule with point H on the dot made through scale D, allowing the edge of the rule to intersect the dot made through scale A, and draw a line at the edge of the rule, which gives the form of the shoulder.

Sixth, place the rule with point J on dot made through scale C, allowing the edge of the rule to intersect the line made from the dots in scale E E; draw a line at edge of the rule; then draw a straight line from the point of intersection of the lines in scale E E to the edge of the fabric, which gives the bottom of the waist.

Seventh, place the rule reverse side up, with point J on the dot made through scale B, moving the rule to the left until it intersects the lines at the back and bottom of the waist and draw-line, which completes the form of the back portion of the waist.

In cutting the separate parts of the waist the lines marked upon the fabric, as heretofore described, are followed in the usual manner.

It will be observed, upon reference to the drawing, that the upper portion of scale 7 7 is less in width, and arranged upon an angle toward the front of pattern from numbers 33 to 31, the object of which is to give a more complete form to the waist for persons of small frame, and especially for children.

Having thus described my invention,

What I claim, and desire to secure by Letters Patent, is—

1. The design or pattern-scale for forming both the front and back of dress-waists, arranged upon one and the same plate, substantially as described and illustrated by the accompanying drawing.

2. The design of the curved rule, employed in connection with said pattern, for laying out the separate parts of the waist, substantially as described and shown in the accompanying drawing.

The foregoing specification of my invention signed by me this 22d day of March, A. D. 1871.

ELIZABETH P. SMITH.
